Primary Examiner — Sandra Snapp*Assistant Examiner* — Leisha Price(74) *Attorney, Agent, or Firm* — Quarles & Brady LLP(57) **CLAIM**

The ornamental design for a fastener, as shown and described.

DESCRIPTION

FIG. 1 is a front view of a fastener showing our new design in accordance with the present invention;
 FIG. 2 is a rear view thereof;
 FIG. 3 is a right side view thereof;
 FIG. 4 is a left side view thereof;
 FIG. 5 is a bottom view thereof; and,
 FIG. 6 is an upper right top perspective view thereof.
 The portions of the fastener shown in broken lines form no part of the claimed design.
